UNITED STATES PATENT OFFICE.

RUSSEL RAY, OF SANTA BARBARA, CALIFORNIA.

DESIGN FOR A CEILING-REFLECTOR.

45,271.

Specification for Design.

Patented Feb. 17, 1914.

Application filed October 15, 1913. Serial No. 795,371. Term of patent 7 years.

To all whom it may concern:

Be it known that I, RUSSEL RAY, a citizen of the United States, residing at Santa Barbara, in the county of Santa Barbara and State of California, have invented a new, original, and ornamental Design for Ceiling-Reflectors, of which the following is a specification, reference being had to the accompanying drawing, forming part thereof.

Figure 1 is a plan view; and Fig. 2 is a

transverse sectional view, showing my new design.

I claim:

The ornamental design for a ceiling reflector as shown.

RUSSEL RAY.

Witnesses:

W.M. G. GRIFFITH,

J. R. HANSEN.
